UNITED STATES PATENT OFFICE.

SILAS BROWNELL BROWN, OF CINCINNATI, OHIO.

TIME-CONTROLLED DAMPER.

No. 870,221.

Specification of Letters Patent.

Patented Nov. 5, 1907.

Application filed January 8, 1906. Serial No. 295,084. Renewed August 30, 1907. Serial No. 390,825.

To all whom it may concern:

Be it known that I, SILAS BROWNELL BROWN, a citizen of the United States, residing at Cincinnati, in the county of Hamilton and State of Ohio, have invented 5 certain new and useful Improvements in Time-Controlled Dampers, of which the following is a specification.

My invention relates to a time actuated damper setting mechanism.

10 One of the objects of the invention is to combine a time releasing and a damper setting mechanism into a simple unitary device which can be conveniently located in any desired part of the house, and which can readily be attached to the base board of the wall or 15 other suitable place.

Another object of the invention is to provide a damper setting mechanism which can be adjusted to any selected position independent of the tripping mechanism but in such relation thereto as to be tripped at the 20 appointed time from any selected position in its range of adjustment.

Various other objects and features of the invention are more fully set forth in the description of the accompanying drawings, forming a part of this specification, 25 in which:—

Figure 1 is a front elevation of my device. Fig. 2 is a rear elevation showing the time releasing portion of the device. Fig. 3 is a section on line *x*, *x*, Fig. 1. Fig. 4 is a section on line *w*, *w*, Fig. 3. Fig. 5 is a detailed view of the sheaves over which the damper chain passes.

1 represents the bracket to which the time releasing and damper setting devices are attached, this bracket being adapted to be secured in a convenient location. 35 The time releasing mechanism is substantially the same as that shown, described and claimed in my former application on time controlled dampers, filed January 30, 1905, Serial #243,263, and I will therefore only describe so much of it as will serve to illustrate its 40 operative functions relative to the other parts of the device of my present application.

2 represents the clock, on the rear of which is a ratchet wheel 3 controlled by time actuated releasing mechanism within the clock. 4 represents a lever 45 pivoted to the bracket 1, having a pawl 5 on its heavier end, adapted to automatically engage into the ratchet wheel 3. 6 represents the lighter end of the lever which is trigger like in shape. This much of the device will be styled the time actuating releasing mechanism. 50 7 represents the member to be released, which is of hook shape adapted to be bodily suspended over the trigger end 6 of lever 4.

In my present invention instead of attaching the damper chain directly to this member 7, I provide a 55 spring control for said member so that it shall be raised to its position of support on the clock releasing mechani-

ism against the tension of the spring, whereby when released it will be retracted to the position shown in Fig. 1. I then provide a tripping mechanism connected to and operated by this spring controlled releasable 60 member 7. I next provide a damper mechanism which has a range of adjustment within the path of movement of the tripping mechanism, but which may be freely adjusted whenever the member 7 is suspended over the clock releasing hook 6 or over a rigid supporting 65 hook 8 on the bracket 1.

The tripping mechanism consists of a rotary trip 9, the front view of which is shown in Fig. 1, and the rear or inside view of which is shown in Fig. 4.

10 represents a tube-like guide way upon the upper 70 end of which seats the member 7.

11 represents a sheave journaled at the lower end of the tube 10.

12 represents a cable one end of which is attached to a lug 13 on the periphery of the trip 9, the said cable 75 passes around the trip 9 within a peripheral groove, and over the sheave 11, its other end being attached to the member 7.

14 represents a plate laterally extended from the bracket 1, having a bearing 15 projected therefrom, 80 upon which the rotary damper setting member 16 journals, see Fig. 3.

17 represents a plate having a hub 18.

The rotary trip 9 is mounted concentrically with the damper setting member 16, being secured to the plate 85 14 by journal bolt 19, see Fig. 3. The trip 9 has an inwardly extending peripheral flange 20, overhanging the hub 18 forming between them a chamber as it were within which lies the coil spring 21, the outer end of which is secured to the periphery of the trip 9 and the 90 inner end of which is secured to the fixed hub 18, see Figs. 3 and 4, so that when the hook 7 is raised to engage either the supports 6 or 8, the trip 9 will turn on its center, imparting a strain to the spring 21, which strain will return the trip to initial position when the 95 member 7 is released by the time release.

The tube 10 is formed with a bumper 22 on one side.

23 represents a tripping lug on the periphery of the member 9, which lug hits against and rests upon the bumper 22 when the trip is actuated.

100 The damper setting member 16 is substantially a sheave having a grooved periphery within which is fixed the damper controlling cable 24, so as to be rotated therewith in either direction. The sheave 16 is of greater diameter than the tripping sheave 9 and has 105 a rotary guide way formed within the plate 14.

25 represents a handle extending outwardly from the periphery of the sheave 16 and projecting to the front of the device for setting the damper, and in position to be intercepted by the tripping lug 23 when member 110 7 is released and moved therewith to the position shown in Fig. 4.

I prefer that one end of the cable 24, the end marked W, in Fig. 1 be attached to the check valve in the furnace flue, while the end marked C, be attached to the damper flap in the furnace door, so that when one is 5 opened the other will be closed.

In operation the member 7 is raised and supported over the hook 6, the lug 23 being moved to the extreme right of the position shown in Fig. 1. The handle 25 can then be rotated freely, the adjustment to the right 10 checks down the furnace, while adjustment to the left starts up the furnace, so that when the handle 25 rests upon the bumper 22 the various damper adjustments are set to obtain the full heating efficiency of the furnace. As the handle 25 and the tripping lug 23 have 15 the same arc of movement it follows that in whatever position the handle 25 is placed it will be intercepted by the lug 23 when the member 7 is released and moved therewith to position against the bumper 22, as shown in Fig. 4, automatically setting the dampers at a pre- 20 determined time to produce the fullest heating efficiency.

It will be observed that the clock and the lever mechanism 4, 5, 6, constitute a time releasing mechanism. The hook 7, cable 12, and spring actuated 25 trip 9, constitute together a tension controlled mechanism, the function of which is to be released by the clock mechanism, so that its trip 23 will engage the damper setting device 25, in any adjusted position, and always move it to a given position. These de- 30 vices so arranged make a very simple and efficient furnace regulator, in which the damper setting mechanism can be adjusted entirely independently.

Having described my invention, I claim:—

1. In a device of the class described, a time releasing 35 mechanism, a tension controlled member to be released having a tripping member, and a damper setting mechanism having no positive connection with the member to be released, and adapted to be independently manipulated, but also adapted to be engaged and operated by the trip at 40 the appointed time.

2. In a device of the class described, a time releasing mechanism, a tension controlled member to be released adapted to be bodily suspended on the time releasing mech-

anism, a trip connected to and controlled by the member to be released, and a damper setting mechanism adapted 45 to be engaged and operated by the trip, substantially as described.

3. In a device of the class described, a time releasing mechanism, a tension controlled member to be released having a tripping member, and a damper setting mechanism 50 having a member adapted to be selectively set in the path of travel of the trip, substantially as described.

4. In a device of the class described, a time releasing mechanism, a member to be released, a rotary spring actuated trip connected to the member to be released, a rotary 55 damper setting mechanism, the said rotary elements being concentrically journaled, and having projections in their coincident path of travel, substantially as described.

5. In a device of the class described, a time releasing mechanism, a member to be released, a swiveled spring 60 controlled trip attached to the member to be released, so as to contract the spring when set, a lug on the periphery of the trip, an abutment against which the lug strikes when the spring is contracted, and a damper setting mechanism having a member adjustable in the path of travel 65 of the tripping lug, substantially as described.

6. In a device of the class described, a time releasing mechanism, a member to be released, adapted to be suspended upon a portion of the time releasing mechanism, a rotary member having a peripheral tripping lug, a stationary abutment adapted to be engaged by said lug, a spring adapted to force said lug normally towards said abutment, a cable connecting the rotary element with the member to be released, and a damper setting mechanism 70 having a member adjustable in the path of travel of said lug, substantially as described.

7. In a device of the class described, a time releasing mechanism, a member to be released, adapted to be suspended upon a portion of the time releasing mechanism, a rotary member having a peripheral tripping lug, a stationary abutment adapted to be engaged by said lug, a spring adapted to force said lug normally towards said abutment, a cable connecting the rotary element with the member to be released, a second rotary member concentrically journaled relative to the first named rotary member, a damper cable engaging said second rotary member, and a peripheral lug projected from said second rotary member 85 into the path of movement of said tripping lug, substantially as described.

In testimony whereof, I have hereunto set my hand.
